IRONING TABLE

Henry T. Yates, Akron, Ohio

Application November 13, 1933, Serial No. 697,868

2 Claims. (Cl. 68—10)

My invention relates to improvements in ironing tables, and particularly to the class of such tables as are collapsible, and its principal objects are, first, to provide a table with large skirt clearance, having supporting legs capable of being folded under the table within its limits, entirely out of the way when folded. A second object is to provide an ironing table of this character, having ease and simplicity of folding operation, and which opens and closes with a single motion, and will not fall apart accidentally when closed, nor self collapse when set up. A third object is to provide a better braced table, the several braces cooperating to produce greater sturdiness and rigidity and endurance, thus affording absolute safety and satisfaction to the user, and at the same time easily foldable for disuse, storage and shipment, and other incidental advantages, all as hereinafter fully set forth and stated in the appended claims.

My invention is illustrated by the accompanying drawing in which similar letters and figures of reference indicate like parts.

Referring thereto, Fig. 1 is a side view of the entire table, opened ready for use. Fig. 2 is a plan view of the table folded together; Fig. 3 is a perspective view of the entire table at an angle; and Fig. 4 is a sectional view of a portion on the dotted line 3—3 of Fig. 3, showing the means for locking and unlocking the foldable members on the under side of the board.

The table 1, its legs or standards 4, 4, and the middle or sloping legs 2, 2 constitute the principal frame work of the device, the legs 2 being of two parts secured together at their lower ends, forming a foot 9. Their upper ends are spread apart and secured pivotally underneath the rear end of the table board 1 to a base strap 1a and clips projecting therefrom, as shown in Fig. 2. The upper ends of the legs 4, 4, are pivotally secured in like manner, so as to be foldable upwardly when collapsed. To enable the legs 4 and 2 to be folded upwardly in unison, a pair of side bars 6, 6, on opposite sides of the table, are each respectively secured to the sloping legs 2 on the pivots 6d, (Fig. 3), about midway between the pivots 4a and 10, and to the hanger bars 6b which depend from the under side of the board 1, a fixed distance, and are pivotally secured thereto on clips 6e.

Each side-bar has an extension bar member 6a, aligned therewith and secured thereto on a pivot 6c at a point about midway between said pivot 6d and its lower end at leg 4 to which it is pivotally secured, as shown in Fig. 3. The arrangement

is such that when the legs 2 and 4, are in open position, as in Figs. 1 and 3, the bars 6, 6a are rigidly aligned between them; and when the board 1 is elevated to horizontal position the hanger bar 6b, attached thereto and to the forward end of the side bar 6, securely holds the legs 2 and 4 apart automatically; and when the board 1 is lowered for folding, the said hanger bars 6b impel said legs together by the action of the side bars 6 on their pivots 6d, crooking said alignment.

Moreover, by the means aforesaid, the legs 4, 4 are inclined rearwardly a limited distance, so as to stand at a slightly obtuse angle with the level of the board 1, and thereby make the structure more rigid.

For a like purpose it is desirable to have the lower ends of the legs stand farther apart than their upper ends, and, when folded, to lie parallel to each other within the limits of the board, so as to be out of the way in handling, storage and shipment.

To accomplish these objects, the following means are provided—The legs 4, 4, are normally spread apart below a limited distance by a pair of bars 13, 13, which pivotally engage the pair of side-bars 6a, respectively, at or near midway between the ends thereof, and toggle joints a, a, in the cross-bars 11, 11, respectively, at their junction with the short members 11b, 11b.

Said pair of cross-bars are pivotally attached to the legs 4, 4, near their upper ends, and at or near the middle thereof, as at b and c, (Fig. 3); and to accommodate the swing of said cross-bars upon their axis 7, they are broken by said toggle joints a, a, respectively, as best shown in Fig. 2, by action of the spreader-bars 13, 13, connected thereto at their upper ends, and at their lower ends to the member 6a of the side-bars 6, 6, respectively, best shown in Fig. 3.

The arrangement and action is such that when the legs 4 are folded upwardly against the board, as in Fig. 2, they are drawn inwardly so as to be parallel therewith, and are spread apart a limited distance at their lower ends and rigidly held apart thereby when unfolded outwardly, as in Fig. 3. The table is supported in open position by means of a support bar 3 which is anchored in the fork of the middle legs 2, on a pivot 10, and is shiftably attached to the underside of the board 1, by means of a short link 3a hinged to a block 3d, so that when the support bar 3 is shifted to the forward position shown in full lines in Fig. 4, the parts are locked and rigidly held therein, and when shifted to the position shown by the dotted lines, 110

all parts are automatically unlocked, and may be folded together simultaneously.

To more effectually brace the several members, the outer ends of the legs 2, 2, are sprung apart 5 in construction, and the long side bars or levers 6 are also sprung by the spreading of the legs 4 when the table is set up; the spreader bars 13 also act forcibly to tension the back cross bars, making a plurality of distinct braces cooperating automatically and simultaneously to support and hold the ironing table in the strongest and most rigid 10 position, incapable of wobbling or break down in use.

The several parts may, of course be modified 15 within the scope of the invention, and I do not limit my claims to mere matter of form. What I claim and desire to secure is—

1. In an ironing table, the combination with a table board, a pair of foldable legs pivotally attached thereto at one end thereof, an intermediate foldable leg split apart at its upper end and pivotally secured to said board adjacent the pivots of said end legs and inclined downwardly therefrom, a pair of side brace-bars, each pivotally connected to its adjacent inclined leg intermediate 25 its ends at a fixed distance from its upper end, a hanger-bar depending from the under side of the board and pivotally secured thereto at about right angles with its adjacent brace-bar to the end 30 of which it is pivotally attached, a short extension-bar pivotally secured to the opposite end of said brace-bar and adapted to fold thereon when the end legs are folded, and pivotally secured to

its adjacent end leg—said several members cooperating to fold and unfold and stabilize said legs, substantially as set forth.

2. In an ironing table, in combination with a board, a pair of foldable legs pivotally secured at one end thereof, an intermediate foldable sloping leg pivotally secured to said board adjacent the pivot of said end legs, a pair of side brace-bars, each pivotally connected to said sloping leg intermediate its ends, a hanger-bar pivotally secured to one end of each brace-bar and to the under side of said board and depending therefrom at about right angles therewith, an extension-bar pivotally secured to the opposite end of said brace-bar and aligned therewith, and to the adjacent end leg and adapted to fold thereon when said legs are folded upwardly—said brace-bars and end members cooperating in folding and unfolding and stabilizing said legs, cross-brace-bars operable between said end legs and pivotally secured thereto at both ends, a toggle joint in each cross-bar near its upper end, and spreader-bar pivotally connected to said toggle joints and to said extension-bars, respectively, to spread apart and stabilize said end legs laterally when unfolded, and a support post for said board anchored at its lower end pivotally to the lower end of said sloping leg, and a reversible link hinged connecting said post and board to permit shifting said upper end longitudinally a limited distance, to lock and unlock and stabilize said foldable members by its reversal, substantially as set forth.
